UNITED STATES PATENT OFFICE.

FRANK BALL, OF CHICAGO, ILLINOIS.

WALL STRUCTURE.

1,211,525.

Specification of Letters Patent. Patented Jan. 9, 1917.

Application filed September 12, 1916. Serial No. 119,672.

To all whom it may concern:

Be it known that I, FRANK BALL, a citizen of the United States, residing at Chicago, in the county of Cook and State of Illinois, 5 have invented new and useful Improvements in Wall Structures, of which the following is a specification.

This invention relates to building walls having a tile facing, and its object is to provide a strong, simple and cheap tile for this 10 purpose, together with novel and improved means for securing the same in place to form the wall.

The invention is illustrated in the accompanying drawing forming a part of this specification, and in said drawing, Figure 1 is a vertical section of a fragment of the wall provided with my improved tile facing; Fig. 2 is a perspective view of a fragment of one 20 of the tiles showing the rear face thereof; Fig. 3 is a similar view showing the outer face of the tile, and Fig. 4 is a view similar to Fig. 1 showing a slight modification.

Referring specifically to the drawing, the 25 tile shown at 5 is a rectangular slab of concrete or analogous material having its top edge formed with a longitudinal ridge 6 extending throughout the entire length of the slab, and having in its bottom edge a corresponding groove 7. The width of the ridge and the groove is less than the thickness of the slab, and the depth of the groove is less than the height of the ridge. Thus, when 30 two of the slabs are placed one above the other, with the ridge of the lower slab seating in the groove of the upper slab, there are left two spaces between the opposite top and bottom edges of the two slabs, one space being in front of the exposed portion of the ridge, and the other space being behind the ridge. The front space is adapted to be 35 filled with a binder 8 of mortar or other suitable material to give the wall a perfectly smooth face.

The slabs 5 are secured by nails 9 to the outside of a wooden or other sheathing 10, with a sheet of tar paper or other moisture insulating material 11 interposed therebetween. The nails are driven diagonally 40 through the tile from the front face of the ridge 6, at the base of the latter, before the binder 8 is applied, the ridge at this point having a recess or countersink 12 to receive

the nail head, with a leather washer 13 under the latter to prevent the slab from cracking 55 when the nail is driven. After the tiles have been nailed in place, the binder 8 is applied, which latter covers the nail heads and gives the wall a perfectly smooth finish.

Fig. 4 shows a slab 5 in all respects similar 60 to the one just described, and secured in the same manner, with the exception that the groove 7 has the same depth as the height of the ridge 6, so that a butt-joint is made, and there is no space between the slabs. The 65 countersink 13 enables the two slabs to be placed closely together in this manner as the nail head is completely housed in the countersink. The nail head is also completely covered. In the first described structure the 70 countersink is not absolutely necessary, as the nail head is below the upper tile and covered by the binder.

In both forms of slabs, the rear face thereof has sunken panels 14 for the relief 75 of expansion or contraction strains in the tar paper 11 and the sheathing 10. Both forms of slabs are also provided with an internal metal reinforcement molded into the same when they are formed. This reinforcement 80 is a piece of wire bent intermediate its ends into a loop or eye 15 and twisted together to form a shank 16, the loop being at one end of the shank. At the other end of the shank the two ends of the wire are spread to extend 85 divergently and in opposite directions from the shank, as shown at 17. The reinforcement is so located that the loop or eye 15 is exposed at the recess 13 so that the nail 9 may be driven therethrough. The reinforcement 90 therefore also serves as an anchor to assist in holding the slab in place.

As the slabs are fastened directly in place by nails, they can be easily and quickly put up. The slabs can also be applied to walls 95 where the siding has become worn or cracked from any cause, by merely removing the siding and nailing on the slabs. Thus, the slabs need not be made thick and clumsy, but thin and inexpensive, as the tar paper and 100 sheathing give a sufficient backing. The surface design of the slabs may be varied as the fancy dictates.

I claim:

A wall composed of a tile facing and a 105 sheathing behind the same, the facing being

composed of slabs having top ridges and bottom grooves, the ridge of one slab seat-
ing in the groove of the next slab, driven
fasteners passing through the slabs into the
5 sheathing from the front faces of the ridges,
and a combined reinforcement and anchor

embedded in the slabs and having loops
which are exposed at the front faces of the
ridges, through which loops the fasteners
are driven.

10

In testimony whereof I affix my signature.
FRANK BALL.
